UNITED STATES PATENT OFFICE.

THOMAS M. PLETCHER, OF FONTANA, WISCONSIN, ASSIGNOR TO THE Q R S MUSIC COMPANY, OF CHICAGO, ILLINOIS, A CORPORATION OF ILLINOIS.

MUSIC-ROLL-BOX CLIP.

Application filed June 14, 1923. Serial No. 645,231.

To all whom it may concern:

Be it known that I, THOMAS M. PLETCHER, a citizen of the United States, having residence at Fontana, in the county of Walworth, in the State of Wisconsin, have invented certain new and useful Improvements 5 in Music-Roll-Box Clips, of which the following is a specification, reference being had to the accompanying drawings, forming a 10 part thereof.

The purpose of this invention is to provide an improved device in the nature of a clip for application to the edge of a box for containing spooled sheet material to hold 15 the sheet from unwinding or slackening on the spool, being particularly designed for applying to a music roll box to hold the coiled note sheet against uncoiling or slackening in the box. It consists in the elements 20 and features of construction shown and described as indicated in the claims.

In the drawings:—

Figure 1 is a top plan view of a music roll box partly broken away disclosing the 25 music roll therein and the clip embodying this invention.

Figure 2 is a section at the line 2—2 on Figure 1.

Figure 3 is a perspective view of the clip 30 in one form.

Figure 4 is a perspective view of the clip in a slightly modified form.

Figure 5 is a view showing Figure 4 from the opposite side.

Figure 6 is a section at the line 6—6 on Figure 5, on an enlarged scale.

In the drawings the roll box is shown at A, the music roll spool therein is shown at B, with the note sheet, C, coiled thereon.

40 The device which constitutes this invention is a sheet metal clip, D, made from a ribbon of sheet metal cut into short strips,—in length about once and a half the depth of the box, A. A short portion, d, at one end 45 of the strip is reflexed upon the strip to form a hook, D¹, whose two sides are spaced apart sufficiently to admit the side of the box between them, that is,—into the recess or loop of the hook, and to cause the hook 50 to grip the box side securely when the clip is thus applied thereto. At a point d² of the length of the strip located as far from the bend, d¹, of the U-clasp or hook terminal, D¹, as the length of the hook terminal, d, the 55 strip is flexed definitely inward with re-

spect to the box, that is, away from the inner wall of the box upon which the clip is applied, and curved or bowed away from the plane of the loop, i. e. convex toward the opposite side of the box, when the clip is mounted, as described, on the box side, the end of said bowed spring finger D² trending back toward the side of the box on which the clip is applied; and, preferably, said end is rolled or coiled closely to 60 form a smooth blunt terminal as seen at d².

For stiffening the device at the bend, d², there is formed a corrugation, d³, extending crosswise of said bend at the inner side 65 thereof.

For improving the grip of the hook or U-clasp, D¹, on the side of the box, and partly to prevent it from slipping too easily on said side, both limbs or sides of the clasp or hook may be corrugated longitudinally, 70 i. e. transverse the bend or fold, d¹, by which the hook is formed,—such corrugations shown at d⁴, Figures 4 and 5, being preferably not abrupt, but only such as render the corrugated part sinuous as seen most clearly 75 in Figure 6, the sinuosity of the two sides of the hook being parallel so that they render the portion of the box edge on which the clip is clasped similarly sinuous without liability to rupturing the pasteboard in 80 applying the clip thereto.

When this clip is applied to the box it will be understood that the insertion of the music roll into the box causes the spring finger D², of the clip to be crowded back 90 toward the side of the box and to press with some force yieldingly against the note sheet coiled on the spool preventing it from uncoiling.

It will further be observed that the form 95 of the clip being made of thin sheet metal as indicated, is such that it does not interfere with applying any sort of cover to the box or telescoping the box into an exterior case.

I claim:

1. In combination with a music roll box and the like container, a clip for checking the roll content of the box against slackening on and uncoiling from the spool, consisting of a piece of sheet metal folded upon itself at one end forming a hook for closely clasping the edge of one side of the box and flexed off from the plane of the hook recess inward with respect to the box cavity, 105 110

- said flexure being made at a distance from the bend which forms the hook sufficient for rendering the depth of the hook adequate to secure a grasp upon the box edge; whereby
- 5 the remainder of the length from said flexor to the limit permitted by the depth of the box forms a spring finger for pressing against the roll.
2. In the construction defined in claim 1
- 10 foregoing, the inner limb of the hook being stiffened at the flexure by a corrugation extending transversely of said flexure and projecting inwardly with respect to the box cavity.
- 15 3. In the construction defined in claim 1 foregoing, the spring finger within the box

being recurved back toward the box side with which the clip is engaged for presenting to the roll a face convex in vertical plane transverse the roll.

20

4. In the construction defined in claim 1 foregoing, the hook portion of the clip having one of its parallel sides longitudinally corrugated so as to be sinuous in cross-section.

25

5. In the construction defined in claim 1 foregoing, the hook portion of the clip having both of its hook sides, longitudinally corrugated so as to be sinuous, the sinuosity of the two sides being substantially parallel with each other.

THOMAS M. PLETCHER.
